UNITED STATES PATENT OFFICE.

CHARLES F. S. BYRNE, OF JANESVILLE, WISCONSIN, ASSIGNOR TO GENERAL MOTORS CORPORATION, OF DETROIT, MICHIGAN, A CORPORATION OF DELAWARE.

ROD AND CROSS-PIN CONNECTION AND METHOD OF MAKING SAME.

1,417,229.

Specification of Letters Patent. Patented May 23, 1922.

Application filed March 8, 1920. Serial No. 364,089.

To all whom it may concern:

Be it known that I, CHARLES F. S. BYRNE, a subject of the King of Great Britain, and a resident of Janesville, county of Rock, and 5 State of Wisconsin, have invented certain new and useful Improvements in Rod and Cross-Pin Connections and Methods of Making Same, of which the following is a full, clear, concise, and exact description, 10 such as will enable others skilled in the art to which the invention relates to make and use the same, reference being made therein to the accompanying drawings, which form a part of this specification.

15 This invention relates to rod and cross pin connections and method of making the same.

One of the objects of the invention is the provision of means for securing a cross pin 20 in its supporting rod, that is simple, efficient and not likely to permit the pin to become detached.

Another object of the invention is to provide a method of securing a cross pin in its 25 supporting rod that is simple, readily accomplished and inexpensive to perform.

Other objects and advantages will appear from the following description and claims.

While I have shown and shall hereinafter 30 describe my device and method of making the same as applied to a starting crank for an internal combustion engine, yet it is understood that this is only one embodiment of my inventive idea, and that I contemplate employing this means in connection 35 with other devices.

In the drawing:

Figure 1 is a side view of a crank for an 40 internal combustion engine;

Figure 2 is a detail view of the inner end of the crank, partly in section, showing the pin in position prior to being secured therein;

Figure 3 is a view similar to Figure 2 45 but showing the pin secured in position;

Figure 4 is a perspective view of the pin; and

Figure 5 is a perspective view of the pin with a modified form of recess.

On the drawing, the numeral 1 designates 50 a crank for an internal combustion engine, 2 the body portion thereof, 3 the handle therefor and 4 the laterally extending engine engaging end. The end 4 is provided 55 with a transversely extending aperture 5 adjacent to its extremity.

A pin 6 having a recess 7 between its ends is placed in the aperture in the end 4. The recess 7 may be of any form, that shown in Figure 4 being arranged transversely to the 60 pin.

After the pin is placed in position in the aperture, metal of the end 4 is distorted into the recess 7. The metal on the side or end may be distorted into the recess but preferably the distortion is made from the end rather than from the side of the rod, since it does not distort the form or shape of the rod. I accomplish this by first countersinking the end of the rod as at 8. This counter- 65 sink 8 may be of any shape, but is preferably conical in form.

When the end of the rod is countersunk, the pin is placed in position with its recess opposite the countersink 8 as shown in Figure 2, and with a punch or other means, metal is distorted into the recess as shown in Figure 3, thus firmly and securely fastening the pin in position.

In the modification shown in Figure 5, the 70 recess 7 is shown as being conical in form. The pin is secured in position in the same manner as the pin 6 in Figure 3.

I claim:

1. The method of securing a cross pin in 85 an apertured rod having a countersink in its end, which consists in forming a recess in said pin, placing said pin in the recess of the rod so that the recess will be opposite said countersink, and distorting the metal 90 beneath said counter sink into said recess.

2. As an article of manufacturing, a rod having its end countersunk and having an aperture therethrough and a pin having a recess, secured in said aperture and having 95 metal adjacent to the bottom of said countersink extended into said recess.

3. A starting crank for internal combustion engines having its end countersunk and provided with an aperture transversely 100 therethrough adjacent to the countersink, a pin in said aperture, and having a recess intermediate the ends thereof, located opposite the bottom of said countersink, and metal adjacent the bottom of said countersink distorted into said recess for securing the pin 105 in said aperture.

In testimony whereof I affix my signature.

CHAS. F. S. BYRNE.
